UNITED STATES PATENT OFFICE.

FREDERICK C. BERWICK, OF NEW YORK, N. Y.

NAUTICAL SIGNAL.

No. 852,594.

Specification of Letters Patent.

Patented May 7, 1907.

Application filed February 5, 1906. Serial No. 299,657.

To all whom it may concern:

Be it known that I, FREDERICK C. BERWICK, a citizen of the United States, residing at New York, in the county of New York and State of New York, have invented certain new and useful Improvements in Nautical Signals; and I do hereby declare the following to be a full, clear, and exact description of the invention, such as will enable others skilled in the art to which it appertains to make and use the same.

The invention relates to nautical signals; and it consists of a novel arrangement of devices whereby an alarm may be sounded and a light flashed simultaneously.

One of the principal objects of the invention is to provide a simple and effective means of warning approaching or passing vessels of possible danger at night or during foggy weather.

Other objects of the invention will be readily apparent upon a complete disclosure thereof.

In the drawing—Figure 1 is a side elevation of my improved signal. Fig. 2 a vertical central section of the lamp. Fig. 3 a top plan of the devices for shielding the light; and Figs. 4 and 5 detail views, showing the arrangement of the operating mechanism.

Referring to the several views, the numeral 1 indicates the sound-producing device, which, in the present instance, is a whistle of the ordinary type, and 2 the lamp. The whistle is mounted upon the upper end 35 of a steam or air pipe 3, connected with any suitable source of supply, and secured to the valve 4 of said whistle is a spring-controlled lever 5, by means of which the steam or air may be allowed to escape through the whistle.

Secured upon the pipe 3 are brackets 6, 6, in which is supported the lamp 2. The lamp may be of any approved shape, preferably cylindrical, and is provided with a bottom plate 7 and a top plate 8, each being provided with suitable air openings. The lamp casing is provided with a storm glass 9, through which the light may be reflected when desired.

In carrying out my invention, I prefer to use acetylene gas or oil as a light-giving flame, and to alternately conceal and flash the light I prefer to employ a pair of oppositely operating shields or shutters 10, 10, al-

though it will be understood that I may employ any device that can be operated to alternately conceal and flash the light.

Each shield is secured to a bottom segment 11, and to an upper segment 12, by rivets 13, as shown in Fig. 2. The bottom segments are pivoted, one upon the other, on a central boss 14 on the upper face of the bottom plate 7, and are held against accidental displacement by a nut 15. The lower or under face of the bottom plate is also provided with a central boss 16, and an aperture is provided for the passage of a gas-pipe 17.

The upper segments are pivoted on a boss 18 on the under side of the top plate 8, and are held against accidental displacement by a washer 19 and a screw 20. Both the lower and upper segments are provided with suitable air passages. The shields or shutters are operated by a three-arm lever 21, movably attached to the upper face of the top plate by a screw 22 passing through a longitudinal slot 23 in said lever. The oppositely disposed arms of the lever are each provided with a longitudinal slot 24, at right angles to the slot 23, through which projects a pin 25, secured to the upper segment, the top plate 80 being provided with a curved slot 26 for each pin. The free end of the third arm of the lever 21 is connected to one arm of a bell-crank lever 27, which is pivoted within an opening 28 of the upper bracket 6. The other arm of the bell-crank lever is connected, by a cord 29, with the free end of the lever controlling the whistle valve, and an operating cord 30 is attached to the other end of said arm.

The valve of the whistle and the shields or shutters being normally closed, a pull on the cord 30 will cause the horizontal arm of the bell-crank lever to move downward, opening the whistle valve to the escape of the air or steam, and the vertical arm of said bell-crank lever to move outward, moving the lever 21 in the same direction and thereby forcing the shields or shutters to move on their pivots in opposite directions, flashing the light simultaneously with the sounding of the whistle.

Various modifications or changes in the details of construction of my invention may be made without limiting the scope thereof.

Having thus fully described my invention

what I claim and desire to secure by Letters Patent, is—

1. In a nautical signal, the combination of a sound-producing device, a signal light, a normally closed valve, a spring-controlled lever normally holding the sound-producing device inoperative, a pair of shields or shutters concealing the signal light, means adapted to alternately open and close the shields, and connections between the spring-controlled lever and the means for opening and closing the shields, whereby an alarm may be sounded and a light flashed.
2. In a nautical signal, the combination of a sound-producing device, a signal light, a normally closed valve, a spring-controlled lever normally holding the sound-producing device inoperative, a pair of shields or shutters concealing the signal light, a three-arm lever and connections adapted to operate

the shields, and a connection between the spring-controlled lever and the three-arm lever, whereby an alarm may be sounded and a light flashed.

3. In a nautical signal, the combination of a whistle, a signal light, a normally closed valve, a spring-controlled lever normally holding the whistle inoperative, a pair of shields or shutters concealing the signal light, a three-arm lever and connections arranged to operate the shields, and a bell-crank lever having one arm attached to the spring-controlled lever and the other arm to the three-arm lever.

In testimony whereof I affix my signature, 35
in the presence of two witnesses.

FREDERICK C. BERWICK.
